Michael Riesner

BY HIS ATTORNEYS

Philip Samuel Rice Meier

UNITED STATES PATENT OFFICE.

MICHAEL RIESNER, OF CINCINNATI, OHIO, ASSIGNOR TO WORTHINGTON PUMP AND MACHINERY CORPORATION, OF NEW YORK, N. Y., A CORPORATION OF VIRGINIA.

COMPRESSOR-UNLOADING MECHANISM.

Application filed January 10, 1921, Serial No. 436,036. Renewed August 8, 1922. Serial No. 580,565.

To all whom it may concern:

Be it known that I, MICHAEL RIESNER, a citizen of the United States, residing at Cincinnati, county of Hamilton, and State 5 of Ohio, have invented certain new and useful Improvements in Compressor-Unloading Mechanism, fully described and represented in the following specification and the accompanying drawings, forming a part of 10 the same.

The present invention relates to improvements in compressor unloading mechanism.

It is the especial object of the invention to provide an improved speed-controlled unloading mechanism for air compressors, by 15 which pressure air is by-passed to the atmosphere through a connection controlled by a valve adapted to cooperate with a governor-controlled pilot valve on a compressor discharge connection, which will 20 permit the compressor driving motor to attain approximately full speed before compressing action begins, and also relieve the pressure when the power is shut off, thereby 25 avoiding jerking strain on the compressor belt or other driving connection, and enabling the efficient use of electric motors for driving the compressor which, while 30 thoroughly efficient at high speeds, would have difficulty in starting up against heavy loads.

With the above objects in view, the invention 35 will now be described in detail in connection with the accompanying drawing and the novel features thereof will then be specifically pointed out in the claims.

The figure of the drawing shows in vertical cross section a compressor cylinder and its discharge or receiver connection with my 40 improved unloading mechanism in a preferred form.

Referring now to the drawing, A indicates the cylinder of a horizontal compressor cylinder with suction and discharge 45 connections B, C, respectively, a, b indicate the suction and discharge valves, respectively, located on the cylinder casting, and c a main discharge check valve of the same character located in the compressor discharge connection C. The valves a, b, c are preferably, and as shown, of the type shown and described in United States reissued Letters Patent No. 13991, dated Oct. 12, 1912, and United States Letters Patent No.

1,341,145, dated May 25, 1920, but may be 55 of any other suitable type.

The means for permitting the compressor driving motor to attain approximately full speed before compressing action begins, comprise a by-pass connection 10 located on 60 the compressor discharge C at a point preferably just below the main check valve c and opening to an atmosphere connection 11 through valve port 12. The port 12 is normally closed by a valve d, shown as of the 65 poppet type, with its plunger 13 working in a casing 14 and held seated by a spring 15 between the plunger and screw cap 16 on the valve casing 14.

The governor controlled pilot valve 70 mechanism comprises a pilot valve e, shown as of a common piston construction, working in a casing 1 provided with ports 3, 4 communicating through pipes 17, 18 with the valve casing 14 above plunger 13 and the 75 compressor discharge C, respectively, the latter connection being at a point in the discharge C above the main check valve c. The ports 3, 4 are closed to each other by valve e when the compressor is not running, 80 the parts being shown in this position in the drawing. The stem of pilot valve e is connected to a speed responsive device, shown as a common centrifugal governor f, driven from the compressor motor in any suitable 85 manner.

It will be obvious that, when the compressor is started and there is no pressure in the receiver, pressure air will first flow 90 through the main check valve c until the receiver pressure is slightly greater than that required to open the port 12 by moving valve d against the pressure of the spring 15, when valve c will remain closed and pressure air will be by-passed to the 95 atmosphere through such port and pipe 11 until the compressor has reached the desired speed, preferably approximately full speed. When the compressor has attained approximately full speed, the governor 100 weights will have raised the pilot valve e so as to connect ports 3, 4 and permit pressure air to flow from the discharge C through pipe 18, ports 4, 3 and pipe 17 to the plunger casing 14, and such air pressure on the larger pressure area of plunger 13 as compared with the area of valve d, 105 supplemented by the pressure of the spring

15, will close the valve *d* and keep it firmly seated against the pressure in by-pass connection 10 and allow air to be compressed through the main check valve *c*. When the 5 speed is reduced, the drooping of the governor weights will move pilot valve *e* to close ports 3, 4 to each other and open port 3 to the atmosphere to relieve the air pressure in the valve casing 14, so that valve *d* 10 is held on its seat only by the pressure of its seating spring and the air will be bypassed to the atmosphere and the load on the motor relieved.

It will be understood that the invention 15 is not limited to the construction shown, but that various changes and modifications may be made therein within the scope of the claims.

What is claimed is:

20 1. A speed controlled compressor unloader mechanism, consisting of a discharge connection from the cylinder, a check valve in said discharge, a low pressure by-pass connection from said discharge at a point 25 intermediate said discharge check valve and the cylinder, a pressure controlled valve controlling said connection, a speed responsive device, and a pilot valve controlled by said device and controlling the pressure on said 30 pressure-controlled valve to permit it to open at low speeds and close the valve when the compressor has attained the speed desired.

2. A speed controlled compressor unloader mechanism, consisting of a discharge connection from the cylinder, a check valve in said discharge, a low pressure by-pass connection from said discharge at a point 35 intermediate said discharge check valve and the cylinder, a by-pass valve controlling said connection and having differential pressure areas, a connection from the compressor discharge above the main compressor check valve adapted to transmit receiver pressure air to the larger pressure 40 area of said by-pass valve, a speed responsive device, and a pilot valve controlling said receiver connection and actuated by said speed responsive device to apply said 45 receiver pressure to hold the by-pass valve closed when the compressor is operating at higher speeds and to open the by-pass valve at low speeds for starting and stopping.

3. A speed controlled compressor unloading mechanism consisting of a discharge connection from the cylinder, a check valve in said discharge, a low pressure by-pass connection from said discharge at a point 50 intermediate said discharge check valve and the cylinder, a valve located in said by-pass having a large pressure area adapted to be exposed to the receiver pressure through a connection thereto and a smaller pressure area constantly exposed to the cylinder pressure, and a speed 55

governor controlled pilot valve and connections for admitting receiver pressure to said by-pass valve casing to hold said valve closed when the compressor is operating at higher speeds and to open the by-pass valve 70 at lower speeds.

4. An unloader for compressors comprising a main valve casing adapted to be connected in the discharge line of a compressor, a main discharge valve controlling the outlet from said casing to the discharge line, automatic means for producing a time element between the starting of the compressor and the opening of said main check valve, and automatic means controlled by the speed of 80 the compressor piston for relieving the pressure remaining in the main valve casing as the compressor comes to a stop.

5. An unloader for compressors, comprising a valve casing adapted to be connected 85 in the discharge line of a compressor, a main discharge valve controlling the outlet from said casing to the discharge line, and operative means connected to said valve casing for automatically unloading and re-loading the 90 compressor controlled only by the speed of the compressor piston.

6. An unloader for compressors comprising a main valve casing adapted to be connected 95 in the discharge line of a compressor, a main discharge valve controlling the outlet from said casing to the discharge line, and automatic means controlled by the speed of 100 the compressor piston for relieving the pressure remaining in the main valve casing, as the compressor comes to a stop.

7. A compressor having a discharge valve, a check valve between said discharge valve and the delivery, and an unloader comprising a pressure controlled unloading valve 105 connected with the discharge line between said compressor discharge valve and check valve, and a speed controlled valve and connections for controlling the pressure on said unloading valve, whereby the load is thrown on and off the compressor in accordance with its speed.

8. A compressor having a check valve in the discharge line and an unloader comprising a pressure controlled unloading valve 115 connected with the discharge line on the compressor side of the check valve, and a speed controlled valve and connections for controlling the pressure on said unloader valve to permit the opening of the valve 120 when the compressor is stopped or running at low speed and to hold said unloader valve closed when the compressor is running at higher speeds.

9. An unloader for compressors, comprising a pressure controlled unloading valve connected with the discharge line of the compressor, a valve for controlling the pressure on said unloading valve, and centrifugal means operated by the compressor for 125

operating said last mentioned valve, whereby the load is thrown on and off the compressor under the control of said centrifugal means.

- 5 10. A compressor having a discharge valve, a check valve between said discharge valve and the delivery, and an unloader comprising a pressure controlled unloading valve connected with the discharge line, and
10 a speed controlled valve and connections for controlling the pressure on said unloading valve whereby the load is thrown on and off the compressor in accordance with its speed.
15 11. A compressor having a check valve in the discharge line and an unloader comprising a pressure controlled unloading valve connected with the discharge line, and a speed controlled valve and connections for
20 controlling the pressure on said unloader

valve to permit the opening of the valve when the compressor is stopped or running at low speed and to hold said unloader valve closed when the compressor is running at higher speeds.

12. An unloader for compressors, comprising a pressure controlled unloading valve connected with the discharge line of the compressor, a speed controlled governor driven by the compressor, a valve controlled by 30 said governor for controlling the pressure on said unloading valve to load and unload the compressor, whereby the load is thrown on and off the compressor in accordance with its speed, and a check valve for preventing the 35 delivery pressure from being imposed upon the compressor after unloading.

In testimony whereof, I have hereunto set my hand.

MICHAEL RIESNER.
